AUTOMATIC TRAIN PIPE CONNECTER

Joseph Robinson, New York, N. Y., assignor of
one-half to Roy M. WolvinApplication November 26, 1934, Serial No. 754,889
Renewed March 14, 1938

13 Claims. (Cl. 285—58)

This invention relates to improved gathering means for automatic train pipe connectors. Among the objects is to provide a connector having a much greater vertical gathering range from 5 points below its center line than from points above its center line, in which the coupling head is arranged to prevent fouling at the top thereof with the inter-engaging coupling parts of the higher connector head as it is drawn down to 10 meet the lower head in the act of coupling under extreme vertical variation, and in which the supporting means of the connector is constructed to prevent undue rotation of the connector heads when coupling at unusual angles and displace- 15 ments. In the present invention this latter feature is particularly important for the reason that under many conditions the inter-engagement of the guiding means is entirely on one side of the longitudinal center line of the connector. When 20 this engagement occurs under extreme displacements the tendency is to rotate one of the guiding devices downward and the other upward. Unless this is prevented the connectors will not couple.

25 In carrying out the object of my invention I employ an improved coupling head having what may be characterized as a third guiding prong or horn. In one embodiment of my invention this horn lies in substantially the plane of the coupling face of the connector head, and in another embodiment it extends forwardly and downwardly and flares laterally from such plane. A further advantage derived from my improvement is that by arranging the major portion of the 30 vertical gathering range of the connector below its horizontal center line, the clearance between the top of the connector head and the bottom of the car coupler is materially improved. This advantage is emphasized when the vertical dis- 35 placements between car couplers is great.

40 In the drawings Figure 1 is a side elevation of my improved connector;

Figure 2 is a sectional plan view of the coupling head thereof and a part of the supporting yoke;

45 Figure 3 is an enlarged sectional front view on the line 3—3 of Figure 1, but with the top of the bracket A broken away;

Figure 4 is a face view of my improved coupling 50 head;

Figure 5 is a sectional elevation on the line 5—5 of Figure 4 showing a modification in the construction of the top portion of the coupling head;

55 Figure 6 is a front elevation of a further modi-

fication of the coupling head of my improved connector, and

Figure 7 is a sectional side view on the line 7—7 of Figure 6.

My improved connector is supported from the 5 underside of the car coupler (not shown) in any convenient way, as by bolting the bracket A to the lug B. The bracket passes downwardly between the spaced straps 1 of the yoke C and is embraced by a rearwardly extending tie rod D by 10 which the connector is pivotally mounted on the bracket for universal movement. Above and below the pivotal point of the tie rod on the bracket I provide laterally extending lugs or projections 15 2 and 3 which are preferably integral with the bracket. These lugs are engaged by flaring webs 4—5 which join the flange 6 and the straps 1. The upper web is curved to the radius through which the yoke C moves when it is lifted vertically about its pivot on the bracket in the act 20 of coupling. To facilitate this vertical movement the flange 6 is shortened below the center line of the yoke and lengthened above the center line as shown at 7 and 8 respectively. Proportioning the flange in this way lessens the re- 25 sistance of the buffer spring E to upward movement of the coupling head whilst increasing such resistance to downward movement, the arrangement being preferably such as to balance these forces in a way that best meets the requirements 30 of service. The buffer spring E surrounds the tie rod D and is seated at one end against the back of the flange 6 and at the other end it rests upon an adjustable abutment or nut F. Preferably the buffer spring has an outside di- 35 ameter which, in relation to the length of the spring, is such as will prevent buckling. This is important for the reason that if the spring E buckles when the connectors couple it will draw one or the other of the straps 1 against the per- 40 forated head 9 of the tie rod causing wear. It will be noted that the webs 4—5 engage the lugs 2—3 at a considerable lateral distance from each other. The purpose of this is to prevent, in co- 45 operation with the radius of the web 4, undue rotation of the connector about its longitudinal axis when coupling under the extreme conditions heretofore mentioned. Considerable rotation is permitted, however, while the connectors are coupled.

The rear bearing face 10 of the bracket is wide and is disposed at an angle to the vertical plane to throw the complementarily wide flange 6 back at its top and tilt the yoke 6 and the coupling head G upward and thus carry the top 11 of the 55

head rearwardly out of the path of the guide wall 12 of a higher head in the downward movement of the latter when coupling under conditions of vertical disalignment. In Figure 5 this clearance 5 is obtained by tilting the top of the funnel 14 rearwardly as at 16a instead of tilting the whole coupling head G and the yoke C as in Figure 1. It may also be secured by flattening the flare of the funnel above the seat 15.

10 As here disclosed my improved coupling head is of the ball and funnel type and includes what may be described as three guiding parts, namely, the short hollow ball member 12, the walls of the shallow funnel 14 that are spaced around the annular bearing or seat 15 in the apex of the funnel, and that portion 16 of the lower part of the funnel which extends from the vicinity of the seat 15 to or beyond the bottom 16a of the head G. The head is suitably mounted, as by pressing, on the 15 forward enlarged hollow end 17 of the yoke C, with the ball member 12 disposed on one side of the longitudinal center line of the connector and the funnel member 14 disposed on the opposite side thereof. A suitable laterally curved fluid conduit 18 is removably mounted, as by a plunger pin 19, in the hollow end of the yoke C and carries a gasket 20 disposed normally in approximately the plane of the coupling face 21 of the head G. The usual train pipe hose 22 is connected to the conduit in the usual way. In certain types of car coupler slip-bys, the funnel member 14 engages the gasket 20 and drags or swipes across its face as it moves out of the slip-by. To prevent damage to the gasket at that 25 time I curve the edges of the funnel rearwardly as at 23.

In the coupling head shown in Figures 1, 2, 4 and 5 the portion 16 hereinbefore described ends in the plane of the coupling face of the head, 40 whilst in the modified form illustrated in Figures 6 and 7 this portion is continued to form a pronounced third guiding member H, that projects forwardly and downwardly of said coupling face and flares laterally a considerable distance from 45 the vertical center line of the connector head G. This extension, or prong, is provided with slots or ways 24 which serve the double purpose of assisting to free the prong from such foreign substances as snow and ice, and of providing guide- 50 ways or paths for the ball 12 to ride along when the connectors meet under conditions of excessive vertical variation. Without these ways the ball sometimes tends to slide laterally off the prong H under these conditions, particularly if 55 the coupling is being made on a curve. The seat 15 comprises a plurality of lugs 25 spaced an equal distance apart with substantial openings 26 between them to also allow the free exit of foreign substance such as snow and ice. These lugs are 60 wedge shaped in cross section narrowing toward the front to provide narrow machined surfaces 27 for engaging the machined face of the ball 12. The reduced width of these surfaces constitute 65 further protection against the interference of snow or ice with the proper seating of these co-engaging parts. If desired the hollow ball member 12 and these lugs may be hardened to minimize wear.

The distance between the seat or bearing 15 70 and the center of the guiding ball 12, and the distance from the center of the seat 15 to the top of the funnel 14, should, of course, be such as to best adapt the coupling head to the various requirements of the service in which it is to be used. 75 Where the lateral displacement or angling of the

couplers is not great, even though the vertical displacement thereof is extreme, the distance between the centers of the ball and the seat may be as little as 10", but if lateral displacements or angling, in combination with vertical displacements, are also great it may be advisable to increase this dimension and the distance from the center of the seat 15 to the top of the funnel. In the interest of compactness it is preferable, however, to hold these dimensions down as much as 10 practicable. To facilitate this the prong H is flared laterally, as shown in Figure 6, to cause it, in cooperation with the similar prong on the opposing connector head, to guide mating coupling heads laterally to assist the balls 12 into their seats when the car couplers are displaced horizontally. The extent of the lateral gathering range of the prong H may be increased or decreased as conditions suggest, and the direction of its flare may be either as shown in solid lines in Figure 6 15 or the prongs may be moved over to the opposite side of the vertical center line of the head and flared in the opposite direction as shown at 28 in dotted lines in that figure.

In assembling the parts of my improved connector the buffer spring E should be compressed sufficiently to force the wide flange 6 firmly against the complementarily wide rear face of the bracket A and to hold the yoke C and the coupling head G yieldingly but securely in the normal uncoupled position shown in Figure 1. The projection of the coupling face of the connector in front of the pulling face of the car coupler should be such as to carry the flange 6, when the connectors couple, away from the back of the 30 bracket A far enough to permit coupled connectors to assume the most extreme conditions of disalignment without endangering the tightness of the joint between mated gaskets 20. 35

What I claim is:

1. An automatic train pipe connector comprising in combination, a coupling head having a greater vertical gathering range from points below its horizontal center than from points above such center whereby increased gathering range in 45 the coupling head is secured, and means to prevent undue rotation of said head about the longitudinal center line of the connector when the co-engaging guiding parts of mating coupling heads meet at points lying within the territory of said 50 increased gathering range.

2. An automatic train pipe connector comprising in combination, a coupling head having a greater vertical gathering range from points below its horizontal center than from points above such center whereby increased gathering range in the coupling head is secured, and means to prevent undue rotation of said head about the longitudinal center line of the connector when the co-engaging guiding parts of mating coupling heads meet at points lying within the territory of said increased gathering range, said means including a yoke on the forward end of which said head is carried, said yoke having its sides spaced relatively widely apart, and a support so spanned 65 by the yoke and having laterally projecting lugs coacting with the sides of the yoke above and below the latter at corresponding widely spaced points laterally of the lugs.

3. An automatic train pipe connector comprising in combination, a coupling head having a greater vertical gathering range from points below its horizontal center than from points above such center whereby increased gathering range in the coupling head is secured, and means to 75

prevent undue rotation of said head about the longitudinal center line of the connector when the co-engaging guiding parts of mating coupling heads meet at points lying within the territory 5 of said increased gathering range, said means including a yoke connected to and carrying said head, a bracket at the rear of said head and engaged by said yoke at relatively widely spaced points at opposite sides of the bracket, and means 10 to prevent rotation of said yoke about its longitudinal axis as mating connectors are coupled, but enabling a substantial degree of rotation during coupled service.

4. An automatic train pipe connector comprising in combination, a coupling head having a greater vertical gathering range from points below its horizontal center than from points above such center whereby increased gathering range 15 in the coupling head is secured, and means to prevent undue rotation of said head about the longitudinal center line of the connector when the co-engaging guiding parts of mating coupling heads meet at points lying within the territory 20 of said increased gathering range, said means including a bracket having an opening in its side and a bearing face disposed at an acute angle to the vertical, a yoke connected to said head and extending rearwardly past said bracket and mounted in said opening, said yoke having a 25 flange engageable with the bearing face of the bracket aforesaid and a spacing web curved complementarily to the arc in which said yoke is adapted to pivot vertically, and means whereby the yoke flange is maintained in engagement with 30 the bearing face of the bracket to normally support the head in an upwardly inclined position when uncoupled, and the web is maintained in engagement with a wall of the opening in said bracket as mating connectors couple under conditions 35 of vertical disalignment.

5. An automatic train pipe connector comprising in combination, a coupling head having a greater vertical gathering range from points below its horizontal center than from points above 45 such center whereby increased gathering range in the coupling head is secured, and means to prevent undue rotation of said head about the longitudinal center line of the connector when the co-engaging guiding parts of mating coupling heads meet at points lying within the territory 50 of said increased gathering range, said head including a forwardly extending guiding prong which lies on one side of the longitudinal center line of the connector, a second guiding member 55 lying on the opposite side of said center line and adapted to receive the prong of a mating head, and a third guiding device projecting downwardly from the bottom of said head for increasing the vertical gathering range of the latter in territories 60 that normally would lie below and hence outside the gathering range of said head.

6. An automatic train pipe connector comprising in combination, a coupling head having a greater vertical gathering range from points below 65 its horizontal center than from points above such center whereby increased gathering range in the coupling head is secured, and means to prevent undue rotation of said head about the longitudinal center line of the connector when 70 the co-engaging guiding parts of mating coupling heads meet at points lying within the territory of said increased gathering range, said head including a forwardly extending guiding prong which lies on one side of the longitudinal center 75 line of the connector, a second guiding member

lying on the opposite side of said center line and adapted to receive the prong of a mating head, and a third guiding device projecting downwardly from the bottom of said head for increasing the vertical gathering range of the latter in territories 5 that normally would lie below and hence outside the gathering range of said head, said last mentioned guiding device being flared laterally of the vertical center line of said head to also increase the lateral gathering range of the head. 10

7. An automatic train pipe connector comprising in combination, a coupling head having a greater vertical gathering range from points below its horizontal center than from points above such center whereby increased gathering range 15 in the coupling head is secured, and means to prevent undue rotation of said head about the longitudinal center line of the connector when the co-engaging guiding parts meet at points lying within the territory of said increased gathering range, said head including a forwardly extending guiding prong which lies on one side of the longitudinal center line of the connector, a second guiding member 20 lying on the opposite side of said center line and adapted to receive the prong of a companion coupling head, and a third guiding device projecting forwardly and downwardly from the bottom of said head, and flaring laterally with respect to the center line 25 of the head, for increasing the vertical and lateral gathering ranges of the head in territories 30 that otherwise would be outside the coupling range of said head.

8. A construction such as described in claim 7 in which said guiding device is provided with 35 ways or paths on a part of its front face for piloting said guiding prong from extreme positions into the area of the normal coupling range of said head.

9. An automatic train pipe connector comprising in combination, a coupling head having a greater vertical gathering range from points below its horizontal center than from points above such center whereby increased gathering range 40 in the coupling head is secured, means to prevent undue rotation of said head about the longitudinal center line of the connector when the co-engaging guiding parts of mating coupling heads meet at points lying within the territory of said increased gathering range, and means normally 45 providing clearance between the top of the coupling head and the guiding parts of a higher mating coupling head when coupling under conditions 50 of vertical disalignment within said territory.

10. An automatic train pipe connector comprising in combination, a coupling head having a greater vertical gathering range from points below its horizontal center than from points above such center whereby increased gathering range 55 in the coupling head is secured, means to prevent undue rotation of said head about the longitudinal center line of the connector when the co-engaging guiding parts of mating coupling heads meet at points lying within the territory of said increased gathering range, and means for 60 holding the top of said head rearwardly upwardly inclined out of the downward path of the guiding parts of a mating head when coupling within said territory.

11. An automatic train pipe connector comprising in combination, a coupling head having a greater vertical gathering range from points below its horizontal center than from points above such center whereby increased gathering range 70 in the coupling head is secured, and means to pre- 75

vent undue rotation of said head about the longitudinal center line of the connector when the co-engaging guiding parts of mating coupling heads meet at points lying within the territory of said increased gathering range, said means including a bracket having an opening in its side, a yoke connected to said head and extending rearwardly past said bracket and mounted in said opening, said yoke having a spacing web 10 curved complementarily to the arc in which said yoke is adapted to pivot vertically whereby the web is maintained in engagement with a wall of the opening in said bracket as mating connectors couple under conditions of vertical disalignment, 15 a flange on the rear end of said yoke and having the major portion of its length disposed above the center line of the yoke, said flange bearing normally against the back of said bracket, and a spring for pressing said yoke forwardly in its bearing on said bracket with said flange normally pressed firmly but yieldingly against the bracket to yieldingly support said yoke and coupling head with greater resistance to downward movement 20 than to upward movement.

12. An automatic train pipe coupling head comprising in combination a base, a plurality of vertically spaced forwardly extending guides connected with said base, the upper guide being disposed on one side of the vertical centerline of the base and the lower guide being disposed on the other side of such centerline and flaring downwardly from said base, a third guiding member lying above said lower guide and receding rearwardly therefrom, and a seat on said third guiding member to receive a part of said upper guide of a mating coupling head when opposing coupling heads couple. 10

13. An automatic train pipe connector, comprising, in combination, a coupling head having a greater vertical gathering range from points below its horizontal center than from points above such center whereby increased gathering range in the coupling head is secured, and means for limiting rotation of the head upon engagement 15 of mating coupling head parts within the vicinity of said increased gathering range. 20

JOSEPH ROBINSON.
